INVENTOR.

Robert B. Smith.

UNITED STATES PATENT OFFICE.

ROBERT B. SMITH, OF STOUGHTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

EYELETING MACHINE.

Original application filed February 7, 1916, Serial No. 76,639. Divided and this application filed January 18, 1917. Serial No. 143,177.

To all whom it may concern:

Be it known that I, ROBERT B. SMITH, a citizen of the United States, residing at Stoughton, in the county of Norfolk and 5 State of Massachusetts, have invented certain Improvements in Eyeletting Machines, of which the following description, in connection with the accompanying drawings, is a specification, like reference characters on 10 the drawings indicating like parts in the several figures.

This invention relates to improvements in machines for setting fasteners and particularly to machines for setting blind and 15 visible eyelets in manufacturing boots and shoes.

By the use of the novel setting device of this invention it is practicable to insert 20 fasteners such as blind or invisible eyelets in shoe uppers after the upper leather and lining parts of the upper have been stitched together along the lacing slit and around the top of the upper, without disturbing the 25 normal relation of those parts of the shoe upper. This is particularly advantageous, as compared with the prior practice of parting the leather and the lining parts after the lacing holes had been punched, so that the eyelets would be set in one or the other 30 of those parts after the fashion of regular visible eyelets, leaving the uneyeleted lacing holes in the other part, in that it provides for performing in a single operation what previously required two separate operations and in that it produces work of a very 35 superior quality.

The novel fastening inserting machine of my invention may be used with advantage in carrying out a method of manufacture 40 consisting in permanently securing together, as by stitching, the leather and lining parts of an upper in that relation which they are to have in the finished shoe, then punching a hole through both parts by the use of a 45 combined punching and setting device, feeding the work without withdrawing the device, and finally inserting an eyelet through

one part of the upper and clenching the eyelet barrel upon the hidden surface of the covered part of the upper. This method is 50 not herein claimed but forms the subject-matter of my co-pending application Serial No. 76,639 filed February 7, 1916, of which the present application is a division.

As herein shown the upper is supported 55 upon a yieldingly mounted cutting block and in a feeding operation the combined punching and setting tool is moved transversely over the surface of the yielding cutting block. This construction prevents the 60 possibility of the work slipping off the end of the punching and setting device during the feeding operation and so contributes to the accuracy and efficiency of the machine.

These and other features of the invention 65 will be best understood and appreciated from the following description of a preferred embodiment thereof selected for purposes of illustration and shown in the accompanying drawings, in which,—

Fig. 1 is a view in perspective of portions 70 of an eyeletting machine of well known construction having my invention embodied therein;

Figs. 2, 3 and 4 illustrate successive steps 75 in the punching, feeding and setting operations; and

Fig. 5 is a view in perspective of a portion 80 of a shoe upper, partly broken away, to show the clenched end of an invisible eyelet.

The machine illustrated in Fig. 1 will readily be identified as the well-known Samson eyeletting machine shown, for example, in United States Letters Patent No. 1,205,- 85 277, granted Nov. 21, 1916, on an application of Walter Shaw. Such portions of the machine as are not herein illustrated may correspond to similar parts of the machine illustrated in said Letters Patent. The machine frame 2 has mounted thereon a lever 90 4 which is arranged to be moved vertically to effect the punching operation and also transversely to effect the feeding operation. The tool 20 mounted in this lever has the

combined functions of punching and feeding the work as well as upsetting or clenching the end of the eyelet barrel. As shown in Figs. 2 and 3 the tool is of tubular construction having an opening extending completely through it to afford passage for the punchings. Its lower edge is shaped to perforate the work in combination with a cutting block 22. A short distance above its end the tool is provided with an outwardly and upwardly curved shoulder 19 which constitutes the upsetting surface. This upsetting surface does not extend sufficiently to engage the prongs of the eyelet barrel during the entire clenching operation and in this sense may be termed an incomplete or restricted upsetting surface or shoulder. Its reduced diameter is, of course, for the purpose of facilitating its introduction through a layer of the work perforated by the tool.

The frame 2 carries a stationary work table 6 perforated for the passage of the setting tools and slotted to receive the punching block 22. The punch block is shown in detail in Fig. 2. It is provided with a downwardly extended shank and is mounted for a limited vertical movement in ways formed in a stationary block 8. The block 8 has sockets for a pair of springs 12 which bear beneath the opposite ends of the block 22 and tend normally to lift it. The normal position of the cutting block is adjustably controlled by a stop screw 14 set in a lug in the lower end of the shank 10 and bearing against the under surface of the stationary block 8. An anti-friction roller 16 is journaled in the block 8 in position to bear upon one side of the shank 10 and thus prevent cramping of the shank and consequent loss of free vertical movement in the cutting block which might result from the pressure of the punch upon the end of the cutting block where the punch would ordinarily act.

The frame 2 is provided with vertical bearings for a plunger 18 in the upper end of which is mounted the lower or eyelet inserting die 17. The inserting die 17 is provided with a center spindle 15 which is adapted to pick one eyelet after another from the end of a raceway 13 preliminarily to each inserting operation. A vertically movable presser foot 11 is provided for holding the work at rest upon the work plate 6 between the feeding operations.

In using the mechanism herein illustrated for setting invisible eyelets the stitched upper is presented upon the work table 6 with the point at which the first eyelet is to be set above the cutting block 22 and in alignment with the tool 20. The machine is thereupon started and the tool is moved downwardly, perforating both parts of the

upper and slightly depressing the cutting block as shown in Fig. 3. The tool 20 is then lifted sufficiently to permit the cutting block to return to its normal position and is then moved transversely toward the left, as shown in Fig. 4, with its end in light engagement with the surface of the cutting block. It will be seen that when the feeding operation is carried out in this manner there is no possibility of the upper slipping off the end of the feeding tool. The feeding operation terminates with the tool 20 in alignment with and above the inserting die 17 to which an eyelet has been supplied by the raceway. In the final step of the cycle the inserting die is elevated and the end of the eyelet barrel forced through the lining part of the upper, being guided by the reduced end portion or pilot of the tool 20 against the upsetting shoulder 19. The position of the tools at the conclusion of the setting operation is shown in Fig. 4.

Having now described my invention together with one method in which it may be used, I claim as new and desire to secure by Letters Patent of the United States:

1. An eyeleting machine having, in combination, a combined punching and setting tool having an upsetting shoulder shaped to be projected through one of several layers of a shoe upper perforated by the tool, and means for inserting an eyelet through the other layer or layers and clenching it against said shoulder.

2. An eyeleting machine having, in combination, a yieldingly mounted cutting block, a combined punching and setting tool having an upsetting shoulder shaped to be projected through one of several layers of a shoe upper supported on said block, and movable transversely of the block to feed the upper, and an eyelet inserting set.

3. In an eyeleting machine, a combined punching and setting tool having a tubular end shaped for punching, and an upsetting shoulder of such small diameter as to facilitate its introduction in the hole formed by the end of the tool and being shaped to form an incomplete upsetting surface.

4. An eyeleting machine having, in combination, a punch, a cutting block extending at one end into line with the punch, springs for supporting the block located adjacent to opposite ends thereof, a shank projecting downwardly from the block, and an anti-friction roller located out of line with the punch and bearing on one side of the shank.

5. In an eyeleting machine, a combined punching and setting tool having a body portion and an upsetting shoulder of relatively small diameter so that it may be inserted into concealed clenching position between the parts of an upper without disturbing the normal relation of the parts, the

body portion of the tool being shaped to support the shoulder in its concealed position.

6. A combined punching and fastener 5 clenching tool having a pilot formed to constitute a punch and merging into a setting shoulder, the setting shoulder being formed

and arranged to follow the pilot portion through one or more of a plurality of layers of material to clench a fastener between adjacent layers of the material. 10

In testimony whereof I have signed my name to this specification.

ROBERT B. SMITH.
